UNITED STATES PATENT OFFICE.

GEORGE WORDINGHAM, OF MILWAUKEE, WISCONSIN.

GARMENT-HANGER.

1,251,948.

Specification of Letters Patent.

Patented Jan. 1, 1918.

Application filed August 23, 1917. Serial No. 187,831.

To all whom it may concern:

Be it known that I, GEORGE WORDINGHAM, a citizen of the United States, residing at Milwaukee, in the county of Milwaukee and State of Wisconsin, have invented certain new and useful Improvements in Garment-Hangers, of which the following is a specification.

This invention relates to garment hangers and has as its object to provide a garment hanger especially adapted for the suspension of skirts, although it may at the same time be employed in hanging coats.

It is one aim of the present invention to provide a garment hanger possessing features which especially recommend it for use by ladies' tailors, cleaners, and dyers for delivery purposes although the hanger is equally as well adapted for wardrobe use.

Where the ordinary hanger or hangers previously devised are employed in the delivery of skirts, the skirt in transportation is liable to become disengaged from the hanger and rumpled in such a manner as to be unsatisfactory to the customer. If clasps are employed upon such a hanger for gripping the waist-band of the skirt they are liable to leave an impression in the goods or to tear or otherwise injure the goods and, in fact, so far as I am aware all previously employed hangers embodying means for preventing disengagement of the skirt from the hanger are liable to injure the skirt or rumple or otherwise leave an impression in the goods. The present invention, therefore, aims further to provide a hanger, which, while adapted to suspend a skirt in a natural draped condition and positively prevent its disengagement from the hanger, will, nevertheless, be in no way likely to injure the goods or leave any impression therein.

Another aim of the invention is to so construct the hanger that the body of the same may be readily and economically produced from sheet material, such, for example, as heavy straw-board or the like, the body being cut from a blank of the material and simultaneously being so cut as to provide the means whereby a skirt may be suspended from the body and securely held against displacement.

Another aim of the invention is to provide a hanger designed for the purpose stated and in which the body of the hanger itself is so cut or formed as to provide the means for holding a skirt against displacement.

ment when suspended from the hanger so that the provision of separate and distinct elements for accomplishing this result is rendered unnecessary and the cost of producing the hanger is materially reduced.

Another aim of the invention is to provide a hanger of the class mentioned so constructed as to afford a maximum area upon which advertising matter may be printed, this, together with the inexpensiveness of the hanger, rendering it especially commercially desirable.

A further object of the invention is to provide a novel means for connecting the suspension hook of the hanger with the body of the hanger, the means being particularly adapted for employment where the body of the hanger is of strawboard or other similar material and being designed to prevent relative turning or rotation of the body and hook.

In the accompanying drawing:

Figure 1 is a front elevation of the hanger embodying the present invention;

Fig. 2 is a horizontal sectional view on the line 2—2 of Fig. 1.

In the drawings, the numeral 1 indicates the body of the hanger, which body may be readily cut in quantities by dies from blanks 85 of thick strawboard or other similar sheet material. The lower edge of the body 1 may be straight or of any other desired contour and the upper edge of the body is preferably inclined upwardly from its ends 90 toward its intermediate portion and then upwardly rounded, as at 2, so that the said upper edge of the body will more or less closely conform to the shoulders of a coat thereby adapting the body to support such 95 a garment. In cutting the body 1 from the blank, or subsequent to the cutting operation, the body is formed with two perforations 3 which are located relatively close to the ends thereof and which, while in the present instance are circular, may be of any other shape. The wall of each perforation 3 substantially touches the upper edge of the body 1 so that there is a thin wall 4 of the material of the body left between 105 the wall of each perforation and the upper edge of the body, this wall portion being, however, so thin that it may be readily broken down by the engagement of the suspension loop or similar part of a garment 110 therewith in the act of forcing the loop into the recess. If desired the wall portion 4

may be formed with an incision 5 at the time of manufacture of the body 1 or such an incision may be formed through the wall portion 4 prior to placing the article upon the market. Or, if desired, the article may be placed upon the market with the wall portion 4 left intact in which event it will be broken down when the loops of a skirt or other similar garment are forced into the perforations 3. As the body 1 is formed from strawboard or other similar fibrous material, the incision 5 in the wall portion 4 of each perforation will remain substantially closed throughout the life of the hanger, although the suspension tape or tapes of a garment may be forced through the incision either in engaging the tape in the perforation or withdrawing the same therefrom. Thus in Fig. 1 of the drawings the reference character S indicates a skirt having suspension tapes or other similar parts, indicated by the reference character T located at its opposite sides and adapted to be drawn through the incisions 5 at the opposite ends of the hanger body and thus engaged in the perforations 3 for the purpose of suspending the said skirt from the hanger. As the material of the body 1 is, as stated, fibrous, the incisions 5 in the walls of the perforations 3 will, as stated above, normally remain closed and, consequently, after the loops T have been engaged in the perforations 3 they will be restrained against accidental disengagement from the perforations and therefore the skirt will not be liable to become accidentally displaced or disengaged from the hanger.

The suspension hook for the body of the hanger is indicated by the numeral 6 and this hook is attached to the body of the hanger by means of a clip which is preferably stamped from sheet metal and which comprises side portions or leaves 7 and a connecting top portion 8. This clip is disposed to straddle the upper edge of the body 1 midway between the ends of the said body and its portions 7 are provided with openings which register with an opening in the said body and through which openings is secured an eyelet rivet 9 which serves to permanently connect the clip with the body. The upper edge of the body 1 beneath the connecting portion 8 of the clip is formed with a notch 10 and the shank 6 of the hook 6 is loosely passed through an opening 11 in the said connecting portion

of the clip and its lower end is bent upon itself, as at 12, to form a relatively broad head which is received within the notch 10 and which is of a width substantially equal to the thickness of the body 1, as clearly shown in Fig. 2 of the drawings. By bending the lower end of the shank of the hook 6 upon itself, as stated, the said end of the shank is anchored in the clip 8 and as the said end of the shank is housed within the notch 10 and is of a thickness equal to the thickness of the body 1 and confined between the side portions 7 of the clip, the said hook is held against turning movement with relation to the said body 1.

Having thus described the invention, what is claimed as new is:

1. In a garment hanger, a flat body provided with a perforation for the engagement therein of a part of a garment, the perforation having a wall substantially touching one edge of the said body whereby the material of the body between the said edge and the wall of the perforation may be readily broken down to provide for ingress of the said part of the garment into the perforation. 75

2. In a garment hanger, a flat body provided with a perforation for the engagement therein of a part of a garment, the perforation having a wall substantially touching one edge of the said body, the body being provided with an incision extending through its portion which lies between the said edge and the said wall of the perforation. 85

3. In a garment hanger, a flat body provided with a notch in its upper edge, a clip disposed to straddle the upper edge of the body thus closing the notch, a suspension hook for the body having a shank fitted through the clip and extending at its lower end into the notch, the said lower end of the shank being bent upon itself to form a broad flat sided head confined within the notch and between the sides of the clip, the head occupying the plane of the body and being of a width substantially equal to the width of the notch and of a thickness substantially equal to the distance between the sides of the clip, whereby the hook as a whole is prevented from rotation with relation to the body. 100

In testimony whereof I affix my signature. 110

GEORGE WORDINGHAM. [L. S.]
